UNITED STATES PATENT OFFICE.

GEORGE A. WILLIAMS, OF WATERBURY, CONNECTICUT, ASSIGNOR TO THE WILLIAMS SEALING CORPORATION, OF WATERBURY, CONNECTICUT, A CORPORATION OF CONNECTICUT.

BOTTLE AND CAP-FASTENER.

1,132,140.

Specification of Letters Patent. Patented Mar. 16, 1915.

Application filed June 1, 1912. Serial No. 701,011.

To all whom it may concern:

Be it known that I, GEORGE A. WILLIAMS, a citizen of the United States, residing at Waterbury, in the county of New Haven and 5 State of Connecticut, have invented a new and useful Improvement in Bottle and Cap-Fasteners, of which the following is a specification.

This invention relates generally to bottle 10 caps, and more particularly to the means for fastening said caps upon the necks of bottles, the object of the invention being to provide a cheap, simple and efficient means for quickly and easily securing the cap, 15 which means can be released when desired and used again and again as required for refitting the caps upon the bottles.

With these various objects in view my 20 invention consists of the novel features of construction hereinafter fully described, pointed out in the claims, and shown in the accompanying drawings in which,

Figure 1 is a perspective view showing the upper end of a bottle neck provided with 25 a cap fastened by one form of my improved fastening means. Fig. 2 is a front elevation of a bottle neck and cap, said cap being fastened by a slightly different form of fastening means. Fig. 3 is a detail sectional view taken on the line 3—3 of Fig. 2. Fig. 4 is a view showing a bottle cap fastened by a slightly different form of fastener. Fig. 5 is a detail perspective view of 30 said fastener detached, while, Fig. 6 shows a still further modified form of fastening device.

Referring to the drawings A, indicates a cap having a slotted skirt carrying a spring ring B, the ends of said ring being carried 40 past each other and bent to provide hooks as shown at B', and between these overlapping hooked ends I introduce a fastening wedge C, which may be either solid or skeleton form and adjacent its wide end is 45 formed with notches or recesses C', so that when the said fastening wedge is forced down the spring ring B, will be tightened thereby clamping the cap upon the neck of the bottle and this downward movement is 50 continued until the hooked ends of the wire ring spring into the recesses or notches C'.

In the construction shown in Fig. 2, the cap A, is provided with a spring ring D, the ends of which are bent back as shown 55 at D', but these ends do not overlap as most

clearly shown in Figs. 2 and 3. These hooked ends are engaged by means of a fastening wedge E, which is in the form of a plate having its side edges rolled over as shown at E', so as to engage the hooked ends D', 60 and by forcing this wedge E, downwardly, it is obvious that the ends of the spring ring are drawn together thereby clamping the skirt of the cap firmly upon the end of the bottle, and adjacent the narrow end of the 65 wedge, recesses or depressions E², are provided into which the hooked ends of the wire ring seat themselves when the locking operation is completed. In this particular structure, the fastening operation is accomplished by forcing the tapering frame or skeleton wedge downwardly so as to contract 70 the spring ring and thereby fasten the skirt of the cap upon the neck of the bottle.

In Fig. 6, I have shown another form of 75 fastening device G, which is in the form of an oval shaped link having notches or recesses G', adjacent its upper end and in practice this link is placed over the hooked ends of the spring ring and is given a movement at right angles to the plane of the fastening ring so as to bring the hooked ends D', 80 into engagement with the notches or recesses G', and the link G, as well as all of the other forms of fastening devices will 85 of course rest against the exterior of the neck of the bottle in its fastened position. and in practice, I prefer to employ a protecting collar H, upon the exterior of the bottle neck and at a point below the lower 90 end of the fastening device, said collar serving to prevent the accidental upward dislocation of the fastening device after the same has once been fastened or secured. Furthermore, a sealing band may be 95 wrapped around the neck of the bottle and the fastening device, and secured to said parts in order to insure the genuineness of the contents of the bottle.

It will be seen that in all of the various 100 forms herein shown and described, the contraction of the spring ring for the purpose of contracting the cap is accomplished by means of a fastening wedge which moves in a plane at right angles to the plane of the 105 ring and in such movement draws or forces the ends of the ring together, thereby contracting said ring and clamping the cap upon the neck of the bottle.

Having thus fully described my invention, 110

what I claim as new and desire to secure by Letters Patent, is:

1. The combination with a bottle having a cap comprising an elastic skirt and a contractile ring, said ring having hooked end portions, of a tapering locking device adapted to engage said hooked ring ends, said locking device being movable bodily in a plane parallel at all times to the bottle neck, said movement in one direction contracting the ring and in the opposite direction expanding the ring.
2. A cap having an expandable and contractile skirt and carrying a ring pro-

vided with hooked ends, a wedge shaped fastening device arranged for engagement with said hooked ends and adapted to move at right angles to the plane of said ring for the purpose of contracting the same, said fastening device being provided with seats for receiving the hooked ends of the ring when the fastening device is in its locked position, as set forth.

GEORGE A. WILLIAMS.
